US0D1113574S

(12) **United States Design Patent** (10) **Patent No.:** **US D1,113,574 S**
(45) **Date of Patent:** **** Feb. 17, 2026**

(54) **BUTTON**

(71) Applicant: **Aparso (Fujian) Sportswear Co., Ltd.**,
Fuzhou (CN)

(72) Inventor: **Rongfu Zhang**, Fujian (CN)

(**) Term: **15 Years**

(21) Appl. No.: **35/521,832**

(22) Filed: **Jun. 18, 2024**

(80) **Hague Agreement Data**

Int. Filing Date: **Jun. 18, 2024**

Int. Reg. No.: **DM/238749**

Int. Reg. Date: **Jun. 18, 2024**

Int. Reg. Pub. Date: **Aug. 2, 2024**

(30) **Foreign Application Priority Data**

Jun. 4, 2024 (CN) 202430338060.9
